United States Patent Office

Des. 206,263
Patented Nov. 22, 1966

206,263

TRUCK

Charles D. Edwards, Elgin, Ill., assignor to B. I. Weller
Co., Chicago, Ill., a corporation of Illinois

Filed Mar. 23, 1966, Ser. No. 1,595

Term of patent 14 years

(Cl. D14—3)

Fig. 1.

Fig. 2.

Fig. 3.

Fig. 4.

FIG. 1 is a side elevational view of a truck embodying my new design;

FIG. 2 is a perspective view of the truck;

FIG. 3 is a rear end view of the truck; and

FIG. 4 is a front end view of the truck.

The dominant features of my design are shown in full lines.

I claim:

The ornamental design for a truck, substantially as shown and described.
